GASEOUS ELECTRIC DISCHARGE DEVICE

Karl Becker, Berlin-Steglitz, Germany, assignor
to General Electric Company, a corporation of
New York

Application November 11, 1932, Serial No. 642,319
In Germany November 25, 1931

7 Claims. (Cl. 176—122)

The present invention relates to gaseous electric discharge devices generally and more particularly the invention relates to such devices in which the gaseous electric discharge is of the concentrated or so-called "stringy" discharge type similar to those described in co-pending application Serial Number 592,138, filed February 10, 1932, which corresponds to British Patent 377,584, the inventors being Marcello Pirani and Martin

10 Reger.

In the application referred to above the concentrated "stringy" discharge is guided along the axis of the container of the device by one or more centrally punctured septums which, by guiding the concentrated discharge, keeps said discharge away from the walls of the container and makes it possible to use a softer and more easily workable glass for the container than would otherwise be practical. The object of the present invention is to improve the efficiency of such devices. Another object of the invention is to simplify the manufacture of such devices. A further object is to facilitate the starting of such devices. Still further objects and advantages attaching to the device and to its use and operation will be apparent to those skilled in the art from the following particular description and from the appended claims.

I have discovered that half-discs are as efficacious as the punctured septums described in the application referred to and that said half-discs do not obstruct the light in at least one direction and, when suitably connected to one of the electrodes of the device, also facilitate the starting of the electric discharge between the electrodes of the device and simplify the manufacture of the device.

In the drawing:—

Fig. 1 is a side elevational, partly sectional view 40 of a gaseous electric discharge device embodying my invention.

Fig. 2 is a sectional view along the line 2—2 of Fig. 1.

Fig. 3 is a side elevational, partly sectional view 45 of another embodiment of my invention.

Fig. 4 is a similar view of still another embodiment of my invention.

Fig. 5 is a sectional view along the line 5—5 of Fig. 4, and

50 Fig. 6 is a side elevational, partly sectional view of another embodiment of my invention.

Like numbers denote like parts in all the figures.

Referring to Figs. 1 and 2 of the drawing the 55 new and novel gaseous electric discharge device

comprises a container 1, having thermionic electrodes 2 sealed therein at each end thereof. Electrode leads 3 of said electrodes 2 are sealed into the pinch parts 4 of stems 5 of said container 1. Said electrodes 2 are of the sintered, mixed metal 5 and oxide type made in accordance with the disclosure of co-pending application, Serial Number 377,044, filed July 9, 1929 being the invention of Marcello Pirani and Hans Ewest, or when desired, any other suitable type of thermionic electrode 10 may be used. Each of said electrodes 2 is surrounded by a metal cylinder 9 which is concentric therewith and which has in the direction of the discharge path a flange with an opening 11 therein. Said opening 11 is concentric with the 15 longitudinal axis of the container 1. Said cylinders 9 are supported by wires or rods sealed in pinch-parts 4 of stems 5. Two half-discs 17 and 18 are arranged on the same side of container 1 perpendicular to the discharge path between said 20 electrodes 2 and are at equal distances along the discharge path between said electrodes 2. The inner rims of said half-discs 17 and 18 are concentric with the longitudinal axis of said container 1 and the outer rims thereof are separated 25 from the inner wall of said container 1 a distance less than the mean free path of an ionized gas particle. Said discs 17 and 18 consist of a metal, such as molybdenum, and, where desired, are degassed. Said discs are attached to the inner wall of the container by small glass beads 19 30 and 20. Said container 1 is filled with an electric discharge conducting gaseous atmosphere such as a mixture of a rare gas, such as neon, and a metal vapor, such as sodium, mercury, or potassium, the body 12 indicating the vaporizable metallic material. Preferably the gaseous atmosphere 35 consists of argon and mercury vapor. Said gaseous atmosphere is at a pressure higher than when a diffuse electric discharge is desired to fill the container 1 between said electrodes 2, for example, a pressure higher than 30 millimeters.

When current is applied across the terminals of the device said electrodes 2 are brought to an electron emitting temperature by an initial gas 45 glow discharge which rapidly changes into the desired mercury vapor arc discharge, or when desired said electrodes are brought to such temperature by a heating filament adapted for that purpose. Due to the high pressure of the gaseous 50 atmosphere the discharge between said electrodes 2 is of the concentrated, "stringy" type and said discharge is guided along the longitudinal axis of said container 1 by the half-discs 17 and 18 and the openings 11 in said cylinders 9. Said 55

discharge is thus prevented from changing its position sufficiently from the normal discharge path between said electrodes 2 to injuriously affect the walls of said container, so that a softer glass may be used in the walls of said container 1 than in a similar device in which the "stringy" electric discharge is not guided. The light emitted by the discharge is unobstructed in its passage through that side of container 1 opposite 10 said half-discs 17 and 18.

The embodiment of the invention shown in Fig. 3 is in all respects similar to that shown in Figs. 1 and 2 with the exception that in this embodiment said half-discs 17 and 18 are arranged 15 near the center of the discharge path between said electrodes 2 and are separated a distance less than the striking distance of the potential applied thereto. Said discs 17 and 18 are partly supported by a tube 21 of heat resisting, insulation material such as a glass or quartz tube. Lead wires 22 and 23 are arranged in said tube 21 and connect said discs 17 and 18 respectively, to one of the leads 3 of the electrodes 2, resistances 24 and 25 being provided in said leads 22 and 25 20 respectively. In this embodiment said discs 17 and 18 act as auxiliary electrodes and facilitate the starting of the main discharge between said electrodes 2 by ionizing the central portion of the discharge path during the starting of the 30 device, and during this starting period a glow discharge takes place between said half-discs 17 and 18. This embodiment of the invention in other respects starts and operates in the manner described in conjunction with Figs. 1 and 2. The 35 leads 22 and 23 are protected during the operation of the device by the quartz tube 21. Where desired, the resistances 24 and 25 can be located in the interior of the lamp unit.

In the embodiment of the invention illustrated 40 in Figs. 4 and 5 the two half-discs 17 and 18 are arranged in the same plane perpendicular to the longitudinal axis of the container 1 of the device and are separated a distance less than the striking distance of the potential applied thereto. 45 In this embodiment said discs 17 and 18 are supported entirely by the quartz tubes 21 and 21' respectively. The inleads 22 and 23 for the half-discs 18 and 17, respectively, are located in said tubes 21' and 21. Said tubes 21 and 21' are supported in said container 1 by wires 26 and 26' 50 respectively sealed into the stems 5. In this embodiment of the invention said half-discs 17 and 18 are free from the inner walls of said container 1 and the insulating, spacing rings 27 and 27', 55 of porcelain, for example, located between said cylinders 9 and said support wires 26 and 26' serve to maintain said tubes 21, 21' in position in said container 1. The embodiment of the invention illustrated in Figures 4 and 5 is similar 60 in operation to that illustrated in Fig. 3. The embodiment illustrated in Figs. 4 and 5 possesses the additional advantage that container 1 may be made as a straight sided tube without the discharge coming dangerously close to the walls 65 of said container 1.

It will be understood from the above description 70 that the invention lends itself to a curved type of container, such as that shown in Fig. 6, in addition to the substantially straight type shown and described in the other figures. Referring to Fig. 6, the electrodes 2 are axially mounted in the ends of the container and the container consists of two substantially parallel tubes 31 and 32 with a curved tube portion 33 connecting said parallel 75 tubes 31 and 32, half-disc 17, 18 or 30 is ar-

ranged at the curved portion in said container along the discharge path in such manner that the "stringy" electric discharge arc path extending from the electrodes 2 to the half-disc 17 or 30 or from one half-disc 17 or 30 to another half-disc 18 is not encroached upon by the walls of the container. The electric arc discharge between the electrodes 2 is thus prevented by the guiding half-discs 17, 18 and 30 from attaching to, or resting on a particular spot on the walls 10 of said container and thus the container walls are protected from injury by the heat of the electric arc discharge between said electrodes 2. A softer, cheaper, and more easily workable glass, therefore, is used as the curved container of an 15 electric discharge device having a "stringy" electric arc discharge than would be practical if the "stringy" electric discharge were not guided and controlled by the means set forth in this invention and the light emitted by the discharge is unob- 20 structed in the direction away from said half-discs 17, 18 and 30.

While I have shown and described and have pointed out in the annexed claims certain novel features of the invention, it will be understood 25 that various omissions, substitutions and changes in the forms and details of the device illustrated and in its use and operation may be made by those skilled in the art without departing from the broad spirit and scope of the invention. 30

What I claim as new and desire to secure by Letters Patent of the United States is:—

1. An electric discharge device comprising a container, thermionic electrodes sealed therein, a gaseous atmosphere therein, and a plurality of 35 metal half-discs along the discharge path between said electrodes, said half-discs being transverse to the discharge path in said container.

2. An electric discharge device comprising a container, thermionic electrodes sealed therein, 40 a gaseous atmosphere therein, said electrodes being surrounded by a cylinder partially closed in the direction of the discharge path and a plurality of metal half-discs along the discharge path between said electrodes, said half-discs being 45 transverse to the discharge path in said container.

3. An electric discharge device comprising a curved container, thermionic electrodes sealed therein, a gaseous atmosphere therein and a plurality of metal half-discs along the discharge 50 path between said electrodes, said half-discs being transverse to the discharge path in said container and mounted at the curved part of said container between said electrodes. 55

4. An electric discharge device comprising a curved container, thermionic electrodes sealed therein, a gaseous atmosphere therein, and a plurality of metal half-discs in said container, 60 said electrodes being in the same plane, said container comprising two parallel portions perpendicular to the plane of said electrodes and a curved portion connecting said parallel portions, said half-discs being mounted along and transverse to the discharge path and at the curved 65 portion in said container, the path of the electric discharge extending from the electrodes to the inner rims of the half-discs and from the inner rim of one half-disc to the inner rim of another half-disc thereby being spaced from the walls of 70 said container.

5. An electric discharge device comprising a container, main discharge supporting electrodes sealed therein, a gaseous atmosphere therein, and a plurality of metal half-discs along the 75

discharge path between said electrodes, said half-discs being transverse to the discharge path in said container to guide the electric discharge between said main electrodes away from the 5 walls of said container and being connected through a resistance to said main electrodes to facilitate the starting of said device.

6. An electric discharge device comprising a container, main discharge supporting electrodes 10 sealed therein, a gaseous atmosphere therein and a plurality of metal half-discs mounted in parallel planes along the discharge path between said main electrodes and transverse to the discharge path in said container to guide the electric dis- 15 charge between said main electrodes away from the walls of said container, each of said half discs being connected to one of said main elec- 20 trodes through a resistance and being separated from the other of said discs a distance such that the potential applied across said discs during the starting period is sufficient to start an electric

discharge therebetween to facilitate the starting of the main discharge between said main electrodes in said device.

7. An electric discharge device comprising a container, main discharge supporting electrodes 5 sealed therein, a gaseous atmosphere therein and a plurality of metal half-discs mounted in the same plane along the discharge path between said main electrodes and transverse to the dis- charge path in said container to guide the elec- 10 tric discharge between said main electrodes away from the walls of said container, each of said half- 15 discs being connected to one of said main elec- trodes through a resistance and being separated from the other of said discs a distance such that the potential applied across said discs during the starting period is sufficient to start an electric dis- 20 charge therebetween to facilitate the starting of the main discharge between said main elec- trodes in said device.

KARL BECKER.
